UNITED STATES PATENT OFFICE.

WILLIAM CARSON, OF SYDNEY, NEW SOUTH WALES, AUSTRALIA.

AMALGAMATING-MACHINE.

1,128,847.

Specification of Letters Patent. Patented Feb. 16, 1915.

Application filed February 24, 1913. Serial No. 750,089.

To all whom it may concern:

Be it known that I, WILLIAM CARSON, subject of the King of Great Britain and Ireland, residing at 60^a Pitt street, Sydney, 5 New South Wales, Australia, have invented certain new and useful Improvements in Amalgamating-Machines, of which the following is a specification.

My invention relates to machines for 10 amalgamating beach sands, battery sand, and like granular products containing gold in a free condition. According to my invention the pulp is passed over a vibrating tray containing a mercury bath and carrying a considerable number of balls of steel 15 or iron free to roll in the mercury. The gold tends to fall to the bottom of the flowing pulp and the balls operate to rub it into the mercury and promote amalgamation. 20 Movement of the pulp over the tray is promoted by the vibrating movement in which the tray is "bumped" against buffer stops.

An embodiment of the said invention is illustrated in the accompanying drawings, 25 the mechanical details of which are however subject to modification.

Figure 1 is a perspective view, Fig. 2 a part longitudinal section and Fig. 3 a fragment section showing a suitable form of vibrating mechanism.

As shown, the machine consists of a tray, the bottom A of which is sheeted with steel or iron, the sides B and C and ends D being of timber which may or may not be reinforced or sheeted with metal. This tray is 35 supported level on four or more flexible metal laths E which as shown are secured at the foot to a suitable frame F. In an alternative arrangement, however, the tray is hung by four or more such flexible metal laths, the upper ends of which are fixed 40 firmly to roof timbers or to an overhead frame construction. In either case the tray is adapted to be vibrated longitudinally, the 45 flexibility of the hanging or standing supports enabling the vibratory movements to occur freely. Instead of pendant laths, chains or links may be used. The beach sands, battery sand or other like products 50 containing free gold are delivered into the tray through a pipe or launder G with spread mouth H. The tailings are delivered out of the lower end of the tray over riffles J and K, L being an apron by which the 55 tailings are directed on to copper plates contained on a fixed table or tray M by

which mercury which is lost from the vibrating tray will be picked up and saved.

The vibrating tray is subdivided with a number of transverse stout wire or rod 60 fences N, and it may be further subdivided if desired by a number of longitudinal fences O of stout wire rods or battens.

Within the inclosures thus formed, solid spheres—balls—of steel or iron P from one 65 to three inches—preferably about three inches—in diameter are loosely placed; they may roll about to a certain extent when the tray is vibrated: In practice each division contains from twelve to twenty balls, suffi- 70

cient to fill the division nearly, there being about one half inch surplus space each way to give clearance for free rolling movement of the balls when the tray is vibrated. The tray is charged with mercury, forming a 75 bath therein as shown at Q, Fig. 2, the precise depth of the mercury bath not being material, but about one eighth to one quarter of an inch being sufficient. The tray is vibrated longitudinally by a quick return 80 crank motion driven from the overhung pin R on the disk S, said pin working in a slot T in the link U, the upper end of said link U being connected by an extensible spring connecting rod V. The delivery end of the 85 tray is armed with bumpers such as W which are disposed to make contact with fixed stops or with buffers, a convenient form of buffer being shown in Fig. 1 consisting of a heavy bar X hung from over- 90 head lines α which tend to hold it forward, and restrained by stirrups Y. The necessary flexibility in the bump is thus obtained, the intensity being regulated by adjusting the length of the stirrups Y. Ob- 95

viously the bumpers may be placed at the end of the tray instead of below it as shown. The vibrating mechanism and the bumper arrangements operate to draw the tray back relatively slowly and allow it to fly back 100 with a quick motion under the drag of the springs v , and also if so arranged by the recoil of the spring supports, until its motion is suddenly arrested by the contact of the bumpers W and stop X. Surging of the 105 mercury over the end of the tray with the tailings is prevented by the riffles J and K of which there may be two. These riffles are canted forward as shown and are about one inch high so as to hold back a depth of 110 flowing pulp over the mercury bath.

The vibratory motion terminating in a

bump at the end of each stroke has the effect of moving the solids forward in the tray and at the same time causing the balls to grind the metallic particles in such manner as to expose and clean the gold surfaces and bring them into intimate contact with the mercury, thereby promoting amalgamation thereof. The pulp fed into the machine is sufficiently liquid to facilitate a very free flow.

In practice the tray is made about ten feet long by three feet wide by four inches deep; but these proportions are not essential to successful operation.

What I claim as my invention and desire to secure by Letters Patent is:—

1. An amalgamator, comprising a flexibly supported tray containing a mercury bath, means dividing said tray into a plurality of

adjacent compartments, a plurality of heavy metal spheres movable in said compartments, and means for imparting abrupt vibrations to said tray.

2. An amalgamator, comprising a flexibly supported tray containing a mercury bath, a series of intersecting fences dividing said tray into a plurality of intercommunicating compartments, a plurality of heavy metal spheres movable in said compartments, and means for periodically imparting abrupt vibrations to said tray.

In testimony whereof I have affixed my signature in presence of two witnesses.

WILLIAM CARSON.
